US0D1003356S

(12) **United States Design Patent** (10) **Patent No.:** **US D1,003,356 S**
(45) **Date of Patent:** **** Oct. 31, 2023**

(54) **GAMING MACHINE**

(71) Applicant: **Aristocrat Technologies Australia Pty Limited**, North Ryde (AU)

(72) Inventors: **Dominic J. DeMarco**, Round Rock, TX (US); **Daniel Harden**, Palo Alto, CA (US)

(73) Assignee: **Aristocrat Technologies Australia Pty Limited**, North Ryde (AU)

(**) Term: **15 Years**

(21) Appl. No.: **29/751,188**

(22) Filed: **Sep. 18, 2020**

Related U.S. Application Data

(62) Division of application No. 29/661,963, filed on Aug. 31, 2018, now Pat. No. Des. 958,888.

CLAIM

We claim the ornamental design for a gaming machine, as shown and described.

DESCRIPTION

FIG. 1 is a front perspective view of a gaming machine showing our new design;

FIG. 2 is a top view of the gaming machine shown in FIG. 1;

FIG. 3 is a front view of the gaming machine shown in FIG. 1;

FIG. 4 is a back view of the gaming machine shown in FIG. 1;

FIG. 5 is a right side view of the gaming machine shown in FIG. 1; and,

FIG. 6 is a left side view of the gaming machine shown in FIG. 1.

In these drawings, the solid lines illustrate the claimed ornamental design, whereas the broken lines illustrate unclaimed environmental features and form no part of the claimed design.

1 Claim, 6 Drawing Sheets
